UNITED STATES PATENT OFFICE

ROBERT M. GETCHELL, OF DAYTON, OHIO, ASSIGNOR TO FRIGIDAIRE CORPORATION, OF DAYTON, OHIO, A CORPORATION OF DELAWARE

REFRIGERATING APPARATUS

Application filed July 30, 1928. Serial No. 296,363.

This invention relates to refrigerating apparatus and more particularly to a refrigerant liquefying unit adapted to be used in a refrigerating system.

5 An object of the present invention is to provide an improved refrigerant liquefying unit which is self-contained and in which the condensing element is air cooled.

10 Another object is to provide an improved location for a fan within the unit so that air circulated thereby will cool the compressing element, condenser, receiver and driving gear.

15 A still further object is to enclose the unit within a unitary structure so as to facilitate manufacture and provide a compact unit which may be readily disassembled.

20 Further objects and advantages of the present invention will be apparent from the following drawings, wherein a preferred form of the present invention is clearly shown.

In the drawings:

Fig. 1 is a view partly in elevation and 25 partly in section of a refrigerant liquefying unit embodying features of my invention.

Fig. 2 is a top plan view of a portion of the unit shown in Fig. 1.

30 Fig. 3 is a view partly in section and partly in elevation, the section being taken along the line 3—3 of Fig. 2.

Fig. 4 is a top plan view of one form of gear pump which may be used in the unit, with the top plate removed.

35 Fig. 5 is a cross-sectional view of the casing shown in Fig. 4, taken along the line 5—5 of Fig. 4.

Fig. 6 is a vertical view in elevation of the gears shown in Fig. 4.

40 Fig. 7 is a top plan view of the bottom plate of the gear pump.

Fig. 8 is a cross sectional view taken along the line 8—8 of Fig. 7.

45 Fig. 9 is a cross sectional view taken along the line 9—9 of Fig. 7.

Fig. 10 is a bottom plan view of the top plate of the gear pump; and

Fig. 11 is a vertical cross sectional view taken along the line 11—11 of Fig. 10.

50 A refrigerant liquefying unit adapted to

be used in this refrigerating system includes a compressor which delivers refrigerant to a condenser, where the refrigerant is liquefied. From the condenser the refrigerant may be delivered to a refrigerant receiver where the liquid refrigerant is stored, ready for use. From the receiver the refrigerant is delivered to an evaporator, for instance of the float controlled valve type, where the refrigerant is evaporated and from which the evaporated refrigerant is returned to the compressor. The refrigerant liquefying unit comprises a compressor generally designated as 20 which delivers the compressed refrigerant to a condenser generally designated as 21 from which the condensed refrigerant is delivered to a refrigerant receiver 22. The liquid refrigerant is delivered from the receiver 22 thru the fitting 23 to an evaporator, not shown, which may be of the float controlled type and from which the refrigerant is returned to the compressor 20. The elements comprising the refrigerant liquefying unit are adapted to be mounted in a vertical or circular casing designated as 30 and having a small dome-shaped portion at its upper end. This casing comprises a bottom cup-shaped section generally designated as 31 on which a ring 32 rests, which ring is a portion of the oil reservoir hereinafter to be described. The section 33 rests on the ring 32 and forms the fan and motor casing. Air for cooling the motor condenser and other parts enters thru openings 34 and comes in contact with the refrigerant receiver 22, the condenser 21 and passes thru an opening 35 in a horizontal plate 36 whence it is driven by the fan 37 out thru the air passage 38 in the dome portion of casing 30. The fan being located in the central portion of the unit has an advantage in that, it increases the velocity of air flow through the unit and tends to cool various parts thereof more rapidly. This velocity increase is due to the fan being mounted in a position whereby, it not only draws air into the unit but also forces air from said unit. Heat generated by the compressing element and driving motor which are located adjacent the path of flow of air is carried away by the circulated air.

The refrigerant from the evaporator is delivered to the compressor 20 in any suitable manner, but it is preferred to pass the refrigerant first thru a seal chamber generally 5 designated as 39 which will be hereinafter more fully described. In order to pass the refrigerant thru this chamber the refrigerant may be received thru a suitable fitting secured to the opening 40 from which it passes thru 10 the passage-way 41 into the seal chamber 39 (see Fig. 2). From the seal chamber 39 it passes thru the passage-way 42 thru the pipe 43 to the intake chamber 44 of the compressor 20. A suitable fitting 45 may be 15 interposed between the pipe 43 and the intake chamber 44. From the intake chamber 44 the refrigerant passes thru the compressor 20 in a manner hereinafter to be more fully described and is delivered in a compressed 20 condition thru the oil reservoir generally designated as 46. The oil reservoir 46 extends over a relatively large area within the unit and lies in the path of circulating air. Air flowing around the reservoir reduces temperature 25 therein and lowers the head-pressure of the refrigerant compressor 20. The outwardly extending portion of pump casing 85 which forms the bottom half of the reservoir 46 is disposed in the path of circulating air 30 and serves as a baffle for directing air over the condenser coil 21. From the oil reservoir 46 the refrigerant is delivered thru the opening 47 and a suitable fitting to the condenser 21 where the refrigerant is liquefied and is 35 delivered in a liquid condition to the receiver 22. The condenser 21 is of spiral form, and includes a plurality of turns of finned tubing connected in series with the receiver 22. The receiver 22 is of a "doughnut" shape, being 40 circular in top elevation and receives the refrigerant from the condenser 21 thru the fitting 48. The receiver 22 is located adjacent the air inlet openings 34 provided in the casing 31 and disposed in the path of 45 flow of air thereby, insuring complete liquefying of gaseous refrigerant which might enter the receiver.

The compressor 20 may be driven by means 50 of the motor generally designated as 50. The motor 50 may be of any suitable construction and may be provided with a rotor generally designated as 51. The fan 37 may be connected in any suitable manner to the rotor 51. A driveshaft 52 may be connected to the rotor 51. The rotor 51 may have an upper bearing 55 which may be lubricated from grease-reservoir 56 around the bearing 55. A suitable spring urged wick 57 may be provided to 60 lubricate the bearing 55 and any excess lubricant may drip on the seal funnel 58 and may be used to augment the lubrication of the seal 54. The drive shaft 52 may be sectional and may be keyed to a second section 65 as at 59. The second section 60 may be keyed

to another section 61 which in turn is keyed to the drive shaft 62 of the compressor 20.

The compressor 20 is of the gear pump variety which is hereinafter described but forms no part of the invention. The pump 70 comprises three gears 63, 64 and 65 carried in bearings 63a, 64a and 65a respectively. The intake of the compressor delivers the refrigerant to the gears in the zone 66. The refrigerant reaches the zone 66 thru an opening 67 in the bottom plate 68. The bottom plate 68 rests on a plate 69 which is the cover for the refrigerant inlet chamber 44. The plate 69 is provided with an opening corresponding with the opening 67 in the plate 68. Part of the refrigerant is pumped to the outlet 70 in the lower plate 68 and the outlet 71 in the upper plate 72 by the gear 63. Another portion of the refrigerant is carried between the teeth of gear 64 around to an intermediate release chamber 73 from whence it is carried by the teeth of gear 65 around to the outlets 70 and 71. The outlet 70 in the lower plate 68 is provided with a horizontal passage-way 73a and a vertical passage-way 74 which is adapted to convey the compressed refrigerant thru the passage-way 75 in the pump casing 76 and on up to the passage-way 77 in the cover plate 72 which delivers the refrigerant to the oil chamber 46. Two outlet passages are thus provided, since the gears are of the herring bone variety and deliver the refrigerant both at the top and bottom of the gears. Both the bottom plate 68 and the top plate 80 90 are provided with release openings 80 which convey the partially compressed refrigerant thru horizontal passages 81 to openings 82 where the refrigerant is caught by the gear 65 and conveyed to the outlets. The end of the passage 81 may be blocked and is bored to the edge of the plate merely because of the convenience in manufacturing. Suitable bolt holes 79 may be provided in the end plates 68 and 72 and the pump casing 76 95 for bolting the parts together.

By providing an intermediate stage 73, the lubricant which slips back thru intermeshing contact of the gears 63 and 65 is arrested in the intermediate chamber 73 105 where a part of the pressure is released thus setting free the greater part of the refrigerant dissolved in the lubricant which is then caught between the teeth of gear 65 and is returned to the outlet.

The gear pump 20 is adapted to be contained in a funnel-shaped casing 85 which forms the bottom half of the oil reservoir 46. The oil in the reservoir 46 may stand at the level about half way in the reservoir. 115 Thus the compressed refrigerant is delivered thru the outlets 71 and 77 bubbles up thru the lubricant and is delivered to the condenser 21 thru the outlet 47. Since the refrigerant bubbles up thru the lubricant, a 120 125 130

spray is avoided in the high pressure chamber 46 as the lubricant acts to prevent the formation of an oil spray. The top of the lubricant chamber 46 is formed by a plate 86 which is surrounded by radial beams 87 on the ring 32. The plate 86 is provided with a casing 88 which forms the seal chamber 39. The seal chamber 39 contains a balanced seal. In general it may comprise a sylphon 89 which carries hermetically connected thereto a bearing ring 90 adapted to cooperate with the stationary ring 91 to form a seal at the joining surfaces. The shaft 52 may be provided with an extension 92 on which the sylphon bellows 89 may be secured as by brazing or the like. The extension 92 cooperates thru the medium of a suitable bearing ring 93 with a stationary ring 94, brazed or other-wise secured to the casing 88. The section 61 of the drive shaft is adapted to fit in this ring 94. Thus it is seen that the seal chamber 39 is subjected to the pressure on the low side of the refrigerating system and is thus interposed between the high pressure side at 46 and the atmospheric pressure at the motor 50. I prefer to make the width of the corrugations of the sylphon 89 equal to the width of the bearing surface of the ring 90. This construction insures a balanced condition of the seal so that it is unaffected by pressure or vacuum conditions in chamber 39. The resilience of the bellows maintains contact between the rings 90 and 91. Suitable oil gauge means may be provided to indicate the height of refrigerant in the lubricant reservoir. As a specific embodiment, passages 101 may be provided as shown in Fig. 2, which passages extend to different levels in the oil reservoir. By providing cocks at the ends of these passages it is possible to determine the height of lubricant by testing the character of refrigerant or lubricant blown out of the passages.

Suitable check valves may be provided, and such check valves may be placed on the suction side of the compressor and if desired, on the high pressure side also.

The different parts as shown may be joined by the use of suitable gaskets and bolts as indicated in the drawings. Thus, for instance, the plates 85 and 86 may have a gasket 95 interposed therebetween and suitable bolts 96 may be provided for assembling these parts together. If desired a part of the casing 31 may be clamped between a suitable ring 97 and the ring 32 by means of bolts 98 which also secure the portion 33 with the ring 32. The lubricant reservoir 56 may be provided with a suitable cover 99. In general, other parts may be secured by bolts or screws as shown in order to form a unit for installation with or in a refrigerating cabinet or for connecting with any other refrigerating system with which it is to be used.

65 By virtue of this construction an efficient

air cooled compressor-condenser unit is provided which is completely enclosed to form a unitary structure and which, may be readily disassembled should it be necessary to repair any part thereof.

70 While the form of embodiment of the invention as herein disclosed, constitutes a preferred form, it is to be understood that other forms might be adopted, all coming within the scope of the claims which follow.

75 What is claimed is as follows:

1. A refrigerating apparatus comprising a vertical casing, a motor and compressor in said casing, a condenser in said casing, a plate located between said motor and compressor adapted to direct air flow in said casing, and a fan driven by said motor adjacent said plate for driving air upwardly through said casing.

80 2. A refrigerating apparatus comprising a vertical casing having air ports therein, a motor and compressor in vertical alignment in said casing, a condenser in said casing, a plate in said casing having a central aperture and located between said motor and compressor, and a fan driven by said motor adjacent said aperture for circulating air through said casing and air ports.

85 3. A refrigerating apparatus comprising a vertical casing having air ports therein, a motor and compressor in vertical alignment in said casing, and a fan located between said motor and compressor for circulating air through said casing and air ports, said compressor including a seal chamber between 90 said motor and compressor, a refrigerant low pressure line leading through said chamber to the intake of said compressor, a lubricant receiver for said seal above said seal chamber, said fan surrounding said chamber and lubricant receiver.

95 4. A refrigerating apparatus comprising a vertical casing having air ports therein, a motor and compressor in vertical alignment in said casing, and a fan located between said motor and compressor for circulating air through said casing and air ports, said compressor including a seal chamber between 100 said motor and compressor, a refrigerant low pressure line leading through said chamber to the intake of said compressor, a lubricant receiver for said seal above said seal chamber, said fan surrounding said chamber and lubricant receiver and a high pressure lubricant and refrigerant reservoir around said chamber.

110 5. A refrigerating apparatus comprising a casing, a motor and compressor in said casing, a condenser within the casing and coiled about the compressor, a fan in said casing, means in the path of air moved by said fan for directing air over the condenser, a second means for directing said air to the central portion of said fan.

115 6. A refrigerating apparatus comprising a 120

casing, a motor and compressor in said casing, a condenser within the casing and coiled about the compressor, a fan in said casing, a portion of said compressor disposed in the 5 path of air moved by said fan for directing air over the condenser, a plate for directing said air to the central portion of said fan.

7. A refrigerating apparatus comprising a casing, a motor and compressor in said casing, a condenser within the casing and coiled about the compressor, a fan in said casing, said compressor provided with an outwardly extending portion disposed in the path of air moved by said fan for directing air over 15 the condenser, a plate having a central aperture adapted to direct said air to the central portion of said fan.

8. A refrigerating apparatus comprising a casing, a motor and compressor in said casing, a condenser within the casing and coiled about the compressor, a fan in said casing, said compressor provided with an outwardly extending portion forming an oil reservoir, 20 said extending portion disposed in the path 25 of air moved by said fan for directing air over the condenser, a plate having a central aperture adapted to direct said air around the reservoir and to the central portion of said fan.

30 9. A refrigerating apparatus comprising a vertical casing having air ports therein, a motor and compressor in vertical alignment in said casing, a condenser in said casing disposed about the compressor, a fan in the casing between said motor and compressor, a plate in said casing having a central aperture and located between said motor and compressor, means in the path of air moved by said fan for directing air over the 35 condenser.

40 10. A refrigerating apparatus comprising in combination, a vertical casing of circular form in cross-section and including a small dome-shaped portion at its upper end, air 45 inlet openings in the lower portion of said casing and air outlet openings in the dome of said casing, a motor within the dome of said casing, a compressor operatively connected with said motor and disposed there- 50 below, a condenser within said casing and surrounding said compressor, a fan for circu- 55 lating air into said casing through said inlet openings and out of said casing through said outlet openings, and means within said casing for directing the circulating air over said condenser.

In testimony whereof I hereto affix my signature.

ROBERT M. GETCHELL.
